United States Patent Office

Des. 191,867
Patented Dec. 5, 1961

191,867

PANEL OR THE LIKE

Allan J. Luck, 220 N. Dale Ave., Mount Prospect, Ill.

Filed May 13, 1959, Ser. No. 55,891

Term of patent 14 years

(Cl. D13—1)

FIG. 1

FIGURE 1 is an edge view of a panel showing my new design, the center being broken away to indicate indeterminate length; and

I claim:

The ornamental design for a panel or the like as shown and described.
